ABSTRACT OF THE DISCLOSURE

Metallic wire card clothing having a narrow bottom edge and an opposite toothed edge is wound in a coil of a plurality of layers. Each layer is helically wound with the clothing standing on its narrow bottom edge. The coil is produced by placing a curved set in the metallic clothing and winding it on a core in helical form in a plurality of layers with the toothed edge being substantially perpendicular to the axis of the core.

This invention relates to a new shipping coil of metallic wire card clothing and to a method of producing such a shipping coil.

Metallic wire card clothing is a thin metal strip of considerable length. Metallic clothing has a narrow bottom edge and opposite this bottom edge is a toothed surface or working surface of the clothing. This surface is a series of substantially uniform teeth punched into the top edge of the metallic clothing. The bottom edge is slightly wider than the toothed edge to provide some rigidity in the clothing. Such metallic clothing is used in various types of carding machines for opening, picking, or carding fibers. In such use it is wound on a metal cylinder in helical form so that there is a surface of teeth as the outer surface of the cylinder. For economic reasons this winding of the metallic clothing on metal cylinders, in some instances, has to be done in various textile mills throughout the world. Generally metallic wire card clothing is shipped in coil form. The simplest way of winding the wire into a coil is to wind it on a core on its flat side with the teeth pointed to one side of the core and to keep winding until you have sufficient wire on the core for economical shipment. With the advent of high speed carding operations it has become more and more important that the metallic wire card clothing have very sharp teeth with good wearing characteristics. In order to produce sharp teeth which have good abrasive life the steel used is usually heat treated and becomes quite brittle. This brittle, heat treated, steel produces a sharp tooth which has long wearing properties. However, in the winding of the wire for shipping in the manner as previously done these very brittle teeth readily break off in the coil. With standard metallic wire card clothing wound in standard form on its side you will generally have anywhere from about 50 to 150 teeth break in a total of about three million six hundred teeth but when you use the harder, more brittle steel teeth this figure will increase to about 1,000 broken teeth. A number of techniques have been tried to reduce this breakage problem such as protecting the teeth with a plastic cap which fits over the teeth. This shows somewhat less breakage but makes for considerably more labor costs in having to install and remove the plastic on some three to four miles of wire in a single coil. Another technique is to place layers of paper or cardboard between each layer of wire and to space the wire across the core so that there is a small space between each wind. This makes the coil very bulky and more expensive to ship and also greatly reduces the speed at which the wire may be wound in order to be able to maintain spacing between winds.

My new coil and the method of manufacture of this

2

coil overcomes the above objections. In my new coil the breakage of teeth is greatly reduced and in fact virtually eliminated during the winding, shipping, and unwinding operation. Furthermore, my new coil has a very uniform wind and hence may be wound into coil form at very high speeds with little difficulty. This extremely uniform wind also makes it quite easy to unwind the coil and rewind it onto the metal cylinder on which it is to be used.

Still an extra advantage of my new coil is that the metallic wire card clothing when wound with the present invention will have a curvature already set into it and hence eliminates this process during the winding of the coil onto the requisite metal cylinder.

In accordance with the present invention metallic wire card clothing in strip form as produced is given a curved set; that is it is given a substantial curve which makes it tend to wind in coil form. The metallic clothing with the set therein is then wound in helical form on a core. A plurality of layers are wound on the core and in each layer the points of the metallic clothing extend outwardly substantially perpendicular to the axis of the core.

The coil produced in accordance with the present invention is a coil of metallic wire card clothing with the metallic clothing having a narrow bottom edge and a toothed top edge substantially opposite each other. The coil comprises a plurality of layers of such metallic clothing with each layer comprising helically wound metallic clothing with each wind having the metallic clothing standing on its narrow bottom edge.

In order that the invention may be clearly understood and more readily carried into effect it is hereinafter described with reference to the accompanying diagrammatic drawings in which:

FIGURE 1 is a cross-sectional view of metallic wire and clothing wound on a core in accordance with the present invention;

FIGURE 2 is an enlarged side view of the metallic clothing;

FIGURE 3 is a cross-sectional view taken along line 3—3 of FIGURE 2;

FIGURE 4 is a schematic view of apparatus for carrying out the method of the present invention; and

FIGURE 5 is an enlarged cross-sectional view taken along line 5—5 of FIGURE 4 showing apparatus useful in placing the curved set into the metallic clothing.

Referring to the drawings, in FIGURE 1 there is shown a spool 10 on which metallic wire card clothing 11 is wrapped in accordance with the present invention. The spool comprises a center rotatable cylinder (core) 12 having a shaft 13 at one end on which a drive pulley 14 is mounted so that the entire spool may be rotated. Mounted on this core in stationary position by suitable key grooves 15 and 16 are two spacing members 17 and 18. The metallic wire clothing is wrapped about the center core between the spaces in a plurality of layers. Each layer comprises a number of helical wraps of metallic wire card clothing with the narrow edge of the first layer of clothing on the surface of the center cylinder and the narrow bottom edge of the second layer of clothing on top of the toothed edge of the first layer and so forth. As shown in the drawings it is preferred that between each layer there is a spacer member 20 which may be made of any suitable material such as thin sheet metal, plastic, cardboard, etc. Layers are wrapped one on top of the other until you reach the outer edge of the spacing members 17 and 18. The wrap should be loose enough so that a spacer 18 may be removed and the entire coil of wire slid off the center core and wrapped for shipment. The rigidity of the wire clothing will hold it in its suitably coiled position as wrapped.

Referring to FIGURES 2 and 3 of the drawings there is

shown the metallic wire card clothing 23 used in the present invention. The clothing comprises a narrow bottom edge 24 and opposite this narrow bottom edge is a toothed edge 25. This is the surface in which the teeth have been punched. To provide rigidity in the card clothing the narrow bottom edge is wider than the toothed edge for about $\frac{1}{4}$ to $\frac{1}{3}$ the height of the clothing forming a shoulder 26. It is the toothed edge which must be made extremely hard and brittle with good wearing or abrasive properties as it is the working surface used in carding fibers. It is these teeth which tend to break off when the metallic card clothing is wrapped in accordance with prior art methods.

Referring to FIGURES 4 and 5 of the drawings there is shown apparatus for carrying the method of the present invention into practice. Prior to winding the metallic wire card clothing on a suitable spool or core it is necessary to place a curved set in the clothing. The purpose of this set is to allow the clothing to be wrapped in a circular manner on its narrow bottom edge rather than flop over and lay on its side. Metallic wire card clothing 30 coming from a punching, heat treating or similar operation is passed over a rotatable surface having circular flanges 32 around its periphery 31. These flanges 32 are spaced a distance apart just slightly greater than the width of the metallic clothing and keep the metallic clothing in an upright position about the surface of the rotatable surface to produce a curved set in the metallic clothing. After the metallic clothing has the curved set placed therein it is wound on a spool or a core 33 as described in accordance with FIGURE 1. The spool is mounted on a suitable frame 34 and is rotated in the direction of the arrows shown. In operation either this spool or the two guiding rotatable rolls are traversed back and forth to wind the metallic clothing on the core in a series of helical winds to form a layer of metallic clothing on the core and a second layer on top of this and so forth.

An enlarged cross-sectional view of a suitable rotatable flanged surface is shown in FIGURE 5. As shown in FIGURE 5 the rotatable surface 39 rotates on a bearing surface 40. The bearing surface is mounted on a rigid shaft 41 which fits the grooved hole 42 in the bearing surface. On the perimeter of the rotatable surface are two circular flanges 43 and 44. These flanges are movable and are set in the desired position by set screws 45. The flanges are positioned in spaced relationship to each other so that the metallic wire 46 passes between the flanges in the upright position as the wire passes about a portion of the periphery of the rotatable surface. The diameter of the rotatable surface may vary from one inch to 3 inches or more. The amount of curved set placed in the metallic wire will depend on the diameter of the rotatable surface and the portion of the periphery of the surface about which the metallic wire passes.

The coils produced in accordance with this invention have wire in which a curved set has already been placed. This means that when this wire is rewound onto a cylinder such as a card main cylinder or a card doffing cylinder no further curvature of set need be placed therein but it may be wound directly from the coil. Furthermore, as shown in FIGURE 1 the high degree of uniformity of the wire on the coil makes for very simple winding on a cylinder and allows higher speed winding and more uniform winding on a cylinder.

In shipping coils made in accordance with the present invention there is very little breakage of teeth. In the prior art coils, i.e., with the wire on its flat side, approximately one thousand teeth will break out of the three million six hundred thousand teeth during the winding, shipping, and unwinding operations of clothing suitable for high speed carding, while in my new coil less than twenty teeth will break in the same operation.

There are also considerable space advantages to my new coils of metallic wire card clothing. Generally, metallic wire card clothing is shipped today in a coil having an inside diameter of $8\frac{1}{2}$ inches and an outside diameter of 23 inches and a thickness of $3\frac{1}{4}$ inches. The wire in such a coil is wound on its side. If it is desired to protect the wire as is required for clothing having a hardness suitable for high speed carding by spacing the wire on its side so that the teeth do not contact other teeth and by placing separators between each layer of the wire it takes approximately three coils having an inside diameter of $12\frac{1}{4}$ inches and an outside diameter of 21 inches, $5\frac{5}{16}$ inches wide to make up the same amount of wire. Compared to this it takes one coil of the present invention having an inside diameter of $12\frac{1}{2}$ inches and an outside diameter of 21 inches, $5\frac{5}{16}$ inches wide to hold the same amount of wire card clothing as the prior art coil. This of course, means great reductions in shipping costs. Furthermore, when winding the wire on its side it takes six times as many spacers as it does when the wire is wound in accordance with the present invention. The larger inside diameter coils are used for two primary reasons; first, to reduce the number of spacers required and second, to hold the curved set placed in the metallic clothing.

With so many very fine teeth it is, of course, extremely difficult to inspect the wire by visual inspection and generally most inspection of the wire is done by feel or hand. When wire is wound on its side it is virtually impossible to inspect the wire until it is taken from the coil and wound on a suitable working cylinder. However, the coil of my invention may be readily inspected merely by feeling each layer of wire as the teeth are all upright and form a suitable inspecting surface for inspection by hand.

Having now described the invention in specific detail and exemplified the manner in which it may be carried into practice it will be readily apparent to those skilled in the art that innumerable variations, applications, modifications, and extensions of the basic principles involved may be made without departing from its spirit or scope.

40 I claim:

1. A coil of metallic wire card clothing said clothing having a narrow bottom edge and a toothed top edge substantially opposite each other and said coil comprising a plurality of layers of metallic clothing each layer comprising helically wound metallic clothing with the tooth points extending substantially perpendicular to the axis of the core.

2. A coil of metallic clothing in accordance with claim 1 wherein there is a spacing member between each layer.

3. A coil of metallic clothing in accordance with claim 1 wherein the metallic clothing has a curved set in it.

4. A method of winding metallic wire card clothing having a narrow bottom edge and a toothed top edge comprising placing a curved set in the clothing and winding 55 the clothing in helical convolutions about a core to form a plurality of layers of clothing on the core with the tooth points extending substantially perpendicular to the axis of the core.

5. A method in accordance with claim 4 wherein a 60 spacing member is placed between each layer as it is wrapped on the core.
